UNITED STATES PATENT OFFICE.

BRUNO PFROMMER, OF REUTLINGEN, GERMANY.

KNITTED FABRIC.

Application filed February 16, 1924, Serial No. 693,295, and in Germany February 23, 1923.

My invention refers to knitted fabrics and more especially to a new kind of plated two-ply knitted fabric, to a process for manufacturing such article and also to the means for carrying out this process.

The new fabric is particularly close and durable and is distorted less easily than other kinds of knitted materials. It is a double-faced fabric showing a uniformly smooth surface on both sides. It can be cut up in any desired manner and does not twine at the edges. If in the ground threads, threads of a different material, different quality or different color are plated, not only costly material can be saved, but a number of peculiar effects can be obtained, for instance in woolen fabrics the felting can be avoided by embedding not-felting threads in the meshes of the wool threads. Furthermore, different color effects can be obtained on the two sides of the fabric, as well as the so-called "shining through" or "watering". The napping of the fabric and also the fulling with cloth-like fabrics can be carried out more advantageously. In every case, the fabric will remain stronger, both in napping and in fulling, than other knitted fabric, inasmuch as the plated meshes which support the meshes of the ground are covered by these latter and are not attacked.

In the drawings affixed to this specification and forming part thereof, my invention is illustrated diagrammatically by way of example. In the drawings

Fig. 1 shows the new fabric in the course of manufacture, while

Fig. 2 is a diagrammatic cross section of the fabric and the needles and

Fig. 3 is a diagrammatic plan view of the fabric, all of them drawn to a larger scale.

Fig. 4 is a plan view, drawn also to a larger scale, of the essential parts of a knitting machine adapted for producing the new fabric and

Fig. 5 is a section on the line A—B in Fig. 4.

Referring to the drawings, the fabric is shown to be composed of three threads, the ground thread *a* and the plated-in threads *b* and *c*. The ground thread *a* which is converted on the two rows of needles into a two-ply ground fabric, emerges on the two surfaces and imparts to the fabric its peculiar character. The plating threads *b* and *c* are formed into meshes with the ground thread

a one-sidedly on each side of the ground fabric, so that on each row of needles a ground mesh and a plated mesh are arranged to form double meshes. The plated meshes *b*, *c* which are arranged inside on each surface of the fabric serve as a filling, binding and as a support against an unnecessary stretching in the longitudinal and transverse direction. This new fabric, which is at the same time soft and full, constitutes an intermediate link between the woven unelastic fabrics and the knitted elastic fabrics.

Different colors are obtained on the two sides of the fabric by employing a thread *b* of different color than thread *c*, these two colors being adapted to the ground color of thread *a*. There is thus obtained a colored shining shade having a so-called reciprocal effect. In this manner three colors can be worked into plated two-ply fabric, whereby a different shade will appear on either side of the fabric.

In the knitting machine, the essential parts of which are illustrated in Figs. 4 and 5, the needles *n*, *n'* are controlled as usual at their heels *f*, *f'* by the cam box, the single parts of which are marked I—VIII and which rotate in the direction of the arrow. *n'* is here assumed to be the front row and *n* the rear row of needles. The middle portions V, VI of the cam box push the needles into their uppermost positions 4 and 7, respectively. The upper parts VII, VIII then pull the needles *n*, *n'* into half-level 5—8, where the needles attain their position of insertion. The thread guide 1, which is of the usual kind, now inserts its threads *a* in the hooks of the needles *n*, *n'* which grip the thread and pull it in order to work it into a row of rib meshes. Besides the thread guide 1 running above and between the needles, there are provided further thread guides 2 and 3 which are running with it, however below the projecting needles, and which separately insert their threads *b*, *c* about one half division later in the row of needles across which they are travelling.

By this peculiar position of the thread guides, each of the plating threads *b*, *c* is inserted one-sidedly in the needle at the side of the ground thread *a* gripped on both sides and are worked together with it by the cam box parts II and III at the place of sinking 6, 9 into meshes.

During this process the natural movements

of the needles on the one hand and the rear portions of the needles on the other hand are utilized for securely inserting the threads *b*, *c*. For, in carrying the needles back, the 5 latches *z*, *z'* are folded in a well known manner by the old meshes against the needle hooks and, while this is being done, the threads *b*, *c* are completely inserted in the hooks and, at the same time, are conducted by the needles 10 which are disposed opposite for the time being at the lower edges of their shafts, so that an escaping of the threads *b*, *c* from the hooks and, in consequence thereof, an uncertain formation of meshes is absolutely avoided. This 15 secure mode of inserting the threads can be clearly seen from Fig. 5 in connection with thread guide 3, intermediate tooth *d*, and needle 4. The knock-over comb, the teeth of which are marked *d'* and *e* provides for the 20 safe producing and knocking-over of the plating meshes.

The three-thread knitting machine allows changing over to another knitting method after the thread guides 2 and 3 have been 25 rendered inoperative and thread guide 1 has been changed over, so that without any loss of time a double rib, royal rib and ribbed fabrics can be made. In the same manner the additional thread guides 2 and 3 can be ex- 30 changed in order to obtain a different color effect.

I wish it to be understood that I do not desire to be limited to the exact details of construction or operation shown and de- 35 scribed, for obvious modifications will occur to a person skilled in the art.

I claim:—

1. As a new article of manufacture, a compound fabric comprising two plain fabric 40 structures and a thread drawn into rib loops to form a rib fabric plating over the loops of said plain fabrics.

2. As a new article of manufacture, a compound fabric comprising two plain fabric 45 structures and a thread drawn into rib loops to form a rib fabric plating over the loops of said plain fabrics, said thread consisting of

a material differing from the material forming said plain fabrics.

3. As a new article of manufacture, a compound fabric comprising two plain fabric structures and a thread drawn into rib loops to form a rib fabric plating over the loops of said plain fabrics, said thread consisting of a material differing in colour from the material forming said plain fabrics. 55

4. As a new article of manufacture, a compound fabric comprising two plain fabric structures formed of different materials and a thread drawn into rib loops to form a rib 60 fabric plating over the loops of said plain fabrics.

5. As a new article of manufacture, a compound fabric comprising two plain fabric structures formed of different materials and a thread drawn into rib loops to form a rib fabric plating over the loops of said plain fabrics, said thread consisting of a material 65 differing from the materials forming said plain fabrics.

6. As a new article of manufacture, a compound fabric comprising two plain fabric structures formed of differently coloured materials and a thread drawn into rib loops to form a rib fabric plating over the loops of 70 said plain fabrics.

7. As a new article of manufacture, a compound fabric comprising two plain fabric structures formed of differently coloured materials and a thread drawn into rib loops to 75 form a rib fabric plating over the loops of said plain fabrics, said thread consisting of a material differing from the materials forming said plain fabrics.

8. As a new article of manufacture, a compound fabric comprising two plain fabric structures formed of differently coloured materials and a thread drawn into rib loops to form a rib fabric plating over the loops of 80 said plain fabrics, said thread consisting of a material differing in colour from the materials forming said plain fabrics. 85

In testimony whereof I affix my signature.
BRUNO PFROMMER.
